(57) **CLAIM**

I claim the ornamental design for the multi-purpose cleaning tool, as shown and described.

DESCRIPTION

FIG. 1 is a perspective view of a multi-purpose cleaning tool showing my new design;

FIG. 2 is a front view thereof;

FIG. 3 is a rear view thereof;

FIG. 4 is a top view thereof;

FIG. 5 is a bottom view thereof; and,

FIG. 6 is a left side elevational view thereof.
